UNITED STATES PATENT OFFICE.

WERNER CHRISTIAN LASSEN HAUBROE, OF COPENHAGEN, DENMARK.

MACHINE-GUN SUPPORT.

Application filed June 19, 1925. Serial No. 38,178.

To all whom it may concern:

Be it known that I, WERNER CHRISTIAN LASSEN HAUBROE, a subject of the King of Denmark, residing at Copenhagen, in the 5 Kingdom of Denmark, have invented new and useful Improvements in Machine-Gun Supports, of which the following is a specification.

The present invention relates to improvements in machine-gun supports of the kind being fitted with a frame consisting of a bottom plate and two vertical side walls, in which the machine-gun is supported by two pairs of pins resting in notches in the side 10 walls of the frame. The distinguishing feature of the invention is that the machine-gun is moveably seated in the frame, in such a manner that overcoming the action of one or more springs it slides some short distance 15 towards the rear in the frame, after each firing owing to the action of that portion of the recoil which has not been consumed in moving back the barrel and the lock and in tightening the recoil springs. Hereby the 20 advantage is attained that during firing the tripod is not forced out from the position in which it has been placed.

On the drawing

Fig. 1 shows, in side elevation, the tripod with the machine-gun resting in the same, and

Figs. 2 to 4, respectively, the frame in side elevation partly in section, in top view and from the rear, to a larger scale.

1 is the rearwardly directed leg of the tripod and 2 the forwardly directed ones. On the leg 1 the elevation adjusting device 3 of the gun support is attached, the said device being connected, by means of rods 4, 35 with a supporting frame 5 in the frame in which the machine gun 6 is resting. This frame consists of a bottom 7 and two side walls 8. In each of the latter there is provided, at front as well as at rear, a slot 9 and 40 10, respectively, in which slots pins 11 and 12 respectively provided on the gun 6 are resting. The said slots are of suitable length and are open upwardly at front, in such a manner that the pins 11 and 12 may easily be 45 passed down into or up from the slots.

In the rear portion of the frame there is provided, between the side walls 8 and in rigid connection with the latter and with the bottom 7, a cross-piece 13 fitted with two 55 holes affording passage for two bolts 15 with heads 14. These bolts are screwed into

threaded holes in a sliding piece 16, and between the cross-piece 13 and each of the heads of the bolts there is provided about each bolt a helical spring 18. The sliding 60 piece may be moved back and forth in the rear portion of the frame 7, 8 in which it is guided by rails 17, and it is fitted with a longitudinal bore 19, Fig. 2, for a bolt 20 passing also through a hood 21, which is 65 screwed into a threaded hole in the cross-piece 13. In front of the front end wall of this hood there is provided a handle 22. Inside of the hood there is provided, about the bolt 20, a helical spring 23, which is held 70 in compression between the front end wall of the hood and an arm 24 keyed onto the bolt 20. The said arm forms, at its upwardly directed end, a hook 25, Fig. 2, which partly 75 engages from above a recess 26 in the upper front portion of the sliding piece 16, in which recess a bolt 27 provided on the gun is resting, when the gun is placed in the frame 7, 8. The hook 25 prevents then the bolt 80 from being pulled up from the recess.

When a shot is fired, the gun recoils, so that its pins 11 and 12 will slide back in the slots 9, and 10, respectively. The bolt 27 connecting the gun to the sliding piece 16 moves then the latter slightly to the rear in the frame 7, 8, whereby the springs 18 become tightened which enables them, when the return motion is completed, to bring the sliding piece and the arm forward again 85 into the normal position in which the front edge of the sliding piece rests against the cross-piece 13. When it is desired to remove the gun from the frame 7, 8 the handle 22 is moved slightly forward, whereby the hook 90 25 is removed from the bolt 27.

Having thus described my invention, what I claim is:—

1. Improvements in supports for machine guns of the kind by which the latter is resting with two pairs of pins in notches in the side walls of a frame, characterized in that a bolt 27 on the gun is connected with a sliding piece 16 adapted to move back and forth in the frame 7, 8 and being actuated by one or more springs 18, which are compressed by the recoil of the gun and the thereby produced motion of the sliding piece in the frame, and which after the recoil has ceased moves the sliding piece and the gun forward again into the normal position.

2. Arrangement according to claim 1, characterized by the attachment to the slid-

ing piece 16 of two bolts passing through holes in a cross-piece 13 fastened to the frame 7, 8 and supporting each a gun returning spring 18 adapted to be compressed between the cross-piece 13 and a head 14 on the bolt.

3. Arrangement according to claim 1, characterized in that the sliding piece 16 is fitted with a longitudinal bore 19 for a bolt 20 supporting an arm 24 fitted with

a hook 25, the said hook while actuated by a spring 23 serving as lock for the bolt 27 of the gun, when the said bolt rests in the sliding piece 16, but being adapted to be released by means of a handle 22 provided on the bolt 20.

In testimony whereof I have signed my name to this specification.

WERNER CHRISTIAN LASSEN HAUBROE.
